*Fig. 4**Fig. 5**To all whom it may concern:*

Be it known that I, Carl Bramming, a citizen of the United States, residing at Nashville, in the county of Davidson and State of Tennessee, have invented a new, original, and ornamental Design for a Lunch Box, of which the following is a specification, reference being had to the accompanying drawings, forming a part thereof, in which:

Figure 1 is a top plan view of the lunch box, showing my new design;

Fig. 2 is an end elevational view thereof;

Fig. 3 is a side elevational view thereof;

Fig. 4 is an elevational view of the opposite side thereof; and

Fig. 5 is a bottom plan view thereof.

The end view, not shown, of the lunch box is the same, reversed from left to right, as the end view shown.

I claim:

The ornamental design for a lunch box, as shown and described.
